UNITED STATES PATENT OFFICE.

NICHOLAS SCHIARIZZI, OF ST. PAUL, MINNESOTA.

RAILROAD-CROSSING.

1,323,411.

Specification of Letters Patent.

Patented Dec. 2, 1919.

Application filed February 28, 1919. Serial No. 279,718.

To all whom it may concern:

Be it known that I, NICHOLAS SCHIARIZZI, a citizen of the United States, residing at St. Paul, in the county of Ramsey and State 5 of Minnesota, have invented new and useful Improvements in Railroad-Crossings, of which the following is a specification.

This invention relates to an improvement in automatic gates designed particularly for 10 the protection of railway crossings, and is directed to a gate of this type wherein the travel of the train will control the lowering and raising of the gate.

It is important that gates of this type be 15 designed to operate when necessary without failure, and where an automatic system can be devised to properly actuate the gate in both directions, to eliminate the human element, a more effective protection is assured.

20 The present gate is designed to operate through electrically controlled instrumentalities, and the current control therefore governed by the passage of the train, so that the train in approaching a protected crossing 25 will automatically lower the gate, and after passing such crossing will automatically raise the gate.

The improved gate is mounted for vertical sliding movement, and to be raised by a 30 motor, means being provided whereby the gate is locked in elevated position. The locking means, which is electrically controlled, is released following a predetermined interval after the train enters the 35 block, so that the gate is released to fall by gravity. The motor is energized following the passage of the train from the block, and acts for a certain time to raise the gate, when the motor circuit is broken, and the 40 gate locked in elevated position, for a subsequent operation.

The invention is illustrated in the accompanying drawings, in which:

Figure 1 is a view in elevation of the improved gate.

Fig. 2 is a side elevation of the main housing, showing the arrangement of the gate frames.

Fig. 3 is a transverse section on the line 50 3-3 of Fig. 1.

Fig. 4 is an enlarged view of the cut-out.

Fig. 5 is a plan of the lock for holding the gate in elevated position.

Fig. 6 is a side view of the same.

55 Fig. 7 is a view of the time switch for energizing the electric lock.

Fig. 8 is a diagrammatic view of the circuits for the system.

Fig. 9 is a view of the spring compensator connected to the cable 11. 60

The improved gate structure is to be arranged adjacent a crossing to protect the same during the passage of a train, and preferably comprises two upright housings 1, at each side of the crossing, and if desired duplicated on each side of the track. These housings are of narrow cross-section, and of the desired height, and one of them has an enlarged base portion in the form of a housing 2, in which the necessary automatic instrumentalities may be arranged 70 for convenient inspection and repair.

Supported within each housing 1, is an upright guide 3, preferably circular in cross section, and adapted for vertical travel on 75 these guides are gate frames 4, comprising uprights 5, having grooved rollers 6, for travel on the guides 3, and horizontal bars 7, projecting from the uprights 5, and through slotted ways 8 in the inner walls 80 of the housings 1. The inner terminals of the bars 7 are connected by any desired form of detail structure to complete the gate.

The upper ends of the guides 3 are provided with supports 9, carrying pulleys 10, 85 over which cables 11 are trained to the upper ends of the uprights 5, the cables 11 extending beyond the pulley 10 toward the housing 2, as a single member. Each cable 11, adjacent its connection with the gate 90 frame, is provided with a spring compensator 12 to avoid breakage of the cable. These compensators are of ordinary type, involving a casing 13, closed at both ends, and having a coiled spring 14 therein, bearing between one end of the casing and a disk 15. The cable 11 passes through the casing, and is provided beyond the disk 15 and toward the gate frame, with a stop element 16 to prevent passage of the cable 100 through the disk beyond a certain point. A slack in the cable may be housed in the casing when the spring is normally extended, so that when the pull comes upon the cable to raise the gate, the initial strain is 105 taken up by the spring. Bumper springs 16' are arranged below the ends of the uprights 5 of the gate frames, to cushion such frames when allowed to drop by gravity.

Arranged in the housing 2 is a motor 17, 110 geared to a winding drum 18, over which latter the cables 11 are wound. An electri-

cally-operated lock 19 is arranged in the upper portion of the housing 2, and comprises a base 20, on which is mounted a fixed block 21, and a support 22, having slidably mounted thereon a sliding block 23. The proximate faces of the blocks 21 and 23 constitute the lock, the coöperating member of which is an inverted cone-shaped member 24 secured on the cable 11 at an appropriate point. The block 23 is spring pressed toward the block 21, so that as the gate is raised the member 24 is forced between the blocks, and after passing below the same is prevented from moving in the opposite direction by the blocks, as will be evident. The movable block 23 is operated against the tension of the spring 25, by a solenoid or the like 26, which when energized will move the block 23 from the block 21, and permit the passage therebetween of the member 24, to thus allow the gate to fall by gravity.

It will be understood that if the system, as is here shown, is to be utilized in connection with the usual block protection, it is not necessary that the gate be permitted to fall immediately the train enters the block. To prevent operation of the lock to release the gate until a predetermined period has followed the entry of the train into the block, there is provided a time switch 27, hereby shown as a casing having a piston moving as a dashpot, and thereby requiring an appreciable interval of time to travel the length of the casing. A solenoid 28 holds the dashpot piston 29 elevated so long as such solenoid remains energized when the solenoid is deenergized the piston 29, when reaching the limit of its free travel closing a switch 30 to the solenoid 26 of the electric lock.

A relay 31 is arranged in the housing 2, in circuit with the respective rails 32 of the track at one end of the block, a battery 33 bridging the rails at the other end of the block. The armature 34 of the relay engages a contact 35 when such relay is energized, and a back contact 36 when the relay is deenergized. The armature is in circuit with one of the service leads, as 37, while the forward contact 35 forms the terminal of a conductor 38. The back contact 36 forms the terminal of a conductor 39, which together with a conductor 40 connected to the other service lead 41, forms a circuit having therein a second relay 42, a horn or other audible signal 43, and a light 44, also serving as a signal. The armature of the second relay 42 is in circuit with service lead 37, and there is provided a back contact 45 for this relay, which leads through conductor 46 to a lock solenoid 60, and thence through conductor 46' to service lead 41. The lock solenoid 60 has its armature 61 spring influenced in

an outward direction, and on the outer end of the said armature is held a holding arm 62. The connection between the arm and the armature is in the nature of a rule joint, and the arm 62 is operated by the armature 29 of the solenoid 28. The armature 61 thus holds the arm 62 in one position until the solenoid 60 is energized to withdraw the said armature. The switch 30 is connected on one side to service lead 41, through conductor 41', and on the other side through conductor 47, through solenoid 26, and to the service lead 37. The motor is in circuit with conductor 38 and service lead 41. This circuit is preferably made through a cut out 48, involving a switch of any ordinary type, having a weight operated handle 49. The handle is engaged by a trip arm 50 on the appropriate gate frame when the gate has reached the desired point of elevation, and the circuit cut, the lowering of the gate permitting the weighted handle to close the switch.

From the above description it will be apparent that when the train enters the block, the relay 31 will be short circuited, and the armature thereof will drop onto the back contact. This will sound the horn, light the light, and energize relay 42. The latter closes the circuit to solenoid 60 and the time switch is put in operation. After a predetermined interval, the switch 30 closes, and the electric lock is opened, and the gate permitted to fall by gravity. As the train leaves the block, the circuit of relay 31 is restored, and the armature engages the forward contact. The horn and light, as well as relay 42 are cut out. The armature of relay 31 through its front contact, energizes the solenoid of the time switch, and such switch is again set, opening switch 30. The electric lock is thus spring held to receive the locking member 24. The motor is energized, and operates the drum to raise the gate, the operation of the motor continuing until the cut-out 48 is operated by the gate.

Having thus described the invention, what is claimed as new, is:—

1. A railway crossing gate, comprising a sliding gate structure, a motor for raising the gate, a lock for holding the gate raised, electrically-operated means for releasing the lock, and a time switch for said means.

2. A railway crossing gate, comprising a sliding gate structure, a motor for raising the gate, a lock for holding the gate raised, a time switch for the lock, and a normally energized track relay for controlling the motor and the time switch.

3. A railway crossing gate, comprising a gate structure adapted to be closed by gravity, a motor for raising the gate, a track relay normally energized, a second relay energized when the track relay is de-

energized, a lock for the gate when raised, electric means for releasing the lock, and a time switch for said means controlled by said second relay.

5. 4. A railway crossing gate comprising a gate structure, a motor for raising the same, a normally energized track relay having forward and back contacts, a motor circuit

controlled through the forward contact, a lock for the gate, a time element for operating the lock to release the gate, and means governing the time element and controlled through the back contact of the track relay.

In testimony whereof I affix my signature.

NICHOLAS SCHIARIZZI.
